HOOK FOR SHOWER FIXTURE

Harold J. Poole, Boca Raton, Fla.
(1601 E. Crest Drive, Charlotte, N.C. 28206)

Filed Dec. 20, 1965, Ser. No. 246

Term of patent 14 years

(Cl. D4—3)

FIG. 1

FIG. 2

FIG. 3

FIG. 4

FIG. 5

FIG. 1 is a side elevation of a hook for a shower fixture, showing my new design.

FIG. 2 is a front elevation thereof.

FIG. 3 is a rear elevation thereof.

FIG. 4 is a top plan view thereof.

FIG. 5 is a bottom plan view thereof.

The shower pipe and head are shown in broken lines for illustrative purposes only.

I claim:

The ornamental design for a hook for shower fixture, as shown and described.
